(57) **CLAIM**

The ornamental design for a tortilla warmer, as shown and described.

DESCRIPTION

FIG. 1 is a top perspective view of a tortilla warmer in an exploded condition showing my new design;

FIG. 2 is a bottom perspective view thereof;

FIG. 3 is a bottom plan view thereof;

FIG. 4 is a top plan view thereof;

FIG. 5 is a side elevation thereof, all other sides being identical thereto;

FIG. 6 is a side elevation view of the tortilla warmer assembled, all other sides being identical thereto; and,

FIG. 7 is a cross-sectional view taken along line 7—7 of FIG. 4 in an exploded condition.
